UNITED STATES PATENT OFFICE.

HAROLD W. EDEN, OF DAVENPORT, IOWA.

WRINGER DRAIN BOARD.

Application filed October 30, 1925. Serial No. 65,777.

My invention relates to washing machine wringers and more especially to the means for guiding clothing into the space between the wringer rolls and carrying water therefrom into the wash tub.

Among the objects of my invention are to provide a construction of the type indicated which can be made to carry the water from the wringer rolls in either direction without longitudinally shifting the drain board in the wringer; to provide a construction of the type indicated which will serve to guide clothing into the space between the wringer rolls; to provide means of the kind designated which will serve to guide the clothing from the wringer rolls into the tub or basket to which said clothing is being directed from the wringer; to provide a construction of the type designated which will carry the water from the wringer to the tub without the water being carried back into the clothing after it has been lifted from the water; to provide a structure of the kind indicated which is easily manufactured and is inexpensive; to improve upon the holding means which retains a tilttable drain board in adjusted position; and such objects, advantages and capabilities as will hereafter more fully appear and as are inherent in the construction disclosed.

My invention further resides in the combination, construction and arrangement of parts illustrated in the accompanying drawing and, while I have shown therein what is now considered the preferred embodiment of my invention, I desire the same to be understood as illustrative only and not as limiting said invention.

In the drawing annexed hereto and forming a part hereof, Fig. 1 is a fragmentary elevation of a wringer with my improved drain board in position therein; Fig. 2 is a transverse section through the frame of this wringer to show more in detail the locking mechanism for the drain board; and Fig. 3 is a vertical longitudinal section through the structure shown in Fig. 1, omitting the wringer rolls and designed to show the pivotal mounting of the drain board and somewhat of the structure thereof.

Referring more in detail to the annexed drawing, numerals 1 and 2 denote the side frame members of the wringer while numeral 3 denotes generally the drain board mounted in the wringer below the wringer rolls 4. The frame members 1 and 2 may be

provided with bosses 5 or, if the frame is made of sufficiently heavy material so that this is not necessary, the pivot rod 6 may be mounted in perforations in the frame members instead of in the bosses 5. If desired, lugs may extend inwardly from the frame to serve as pivotal means for the drain board but this is not considered as desirable as the construction here disclosed. In Figs. 65 1 and 2 I show a lug 7 extending laterally from the frame member 2. This lug is hollowed out and perforated for the reception of a spring pressed plunger 8 provided with a head 9 for retracting the plunger so that the drain board may be tilted from one inclined position to another, as will be readily understood. The plunger is adapted to enter a depression or perforation 8a in the flange 11 (shown in Fig. 1) or to engage beneath 75 the drain board as shown in said figure.

The drain board itself is what may be called a double drain board and has a lower member 10 provided at its two ends with flanges 11 which are either integral with the lower member or are secured thereto, preferably the former. The flanges are shown as notched at 12 to provide space for the rocking of the drain board on its pivot rod 6, to which the drain board is held by means 13, here shown as a bent plate secured to the underside of the lower member. The flanges 11 extend upwardly some distance from the lower member and have upper members 14 and 15 secured thereto below the upper edges 98 of the flanges. These upper members 14 and 15 may be considered guide members for guiding clothing into the rolls and from the rolls into a tub or basket. Members 14 and 15 are turned downwardly as shown at 16 95 and 17 to serve as guards for the front and back edges of the bottom member 10. These parts 16 and 17 also prevent, to a certain extent, the water which leaves the drain board from passing outwardly into the clothing which is rising from the tub. Also, these parts serve to strengthen the upper members 14 and 15 and prevent them from being too easily bent. As indicated at 18, space is provided between the upper and lower members for the exit of water which collects 100 inside the wedge shaped pockets of the drain board. If desired, the bottom plate 10 and the upper plates 14 and 15 could be made integral and the structure could be provided with perforations at the points 18 for the escape of water from the interior of the drain

board, but this is not considered as desirable as the construction here shown.

The inner edges of upper members 14 and 15 are turned downwardly as indicated at 5 19 to avoid any sharp edge at this point on which one's hands might become injured. These flanges 19 also serve to reinforce the inner edges of these members and prevent them from becoming easily bent. In the 10 construction illustrated perforations are provided in the flanges 11 and projections 20 upon the ends of the upper members extend into these perforations and are riveted therein to hold the upper members in position.

15 This is considered preferable to having these upper members provided with downwardly extending flanges which are riveted to the inner faces of the flanges 11. Various other constructions will suggest themselves to one skilled in the art and they are therefore not detailed herein. It is obvious that part of the water carried up by the clothing lifted from a tub will run down the upper surface of plate 14 or 15, depending upon which direction the board is inclined.

20 It is believed that my disclosure is sufficient to show that the present construction will accomplish the various objects set forth above and that the operation of this device will be apparent without further reference thereto.

Having now described my invention,

I claim:

25 1. In a wringer having a frame and wringer rolls mounted therein, pivot means on the frame and a drain board pivotally mounted thereon, said drain board having upper and lower water directing surfaces, 40 the lower water directing surface being included within the extreme limits of the upper surface.

2. In a wringer having a frame and wringer rolls mounted therein, pivot means 45 on the frame and a drain board pivotally mounted thereon, said drain board having upper and lower water directing surfaces, the lower water directing surface terminating within the extreme limits of the upper 50 surface.

3. In a wringer having a frame and wringer rolls mounted therein, pivot means on the frame and a drain board pivotally mounted thereon, said drain board comprising 55 a bottom member, end members extending upwardly from the bottom member and top members extending between the end members and spaced from the bottom member and covering a substantial part thereof, the extreme edges of the top members being 60 bent downwardly to overlap the spaces between the extremities of the bottom and top members.

4. In a wringer drain board, a bottom

member, end members rising from two edges 65 thereof, and guide members spaced from the bottom member and covering the front and back edges thereof, said guide members, at their outer extremities approaching the bottom member and at their inner edges being 70 farther from the bottom member, and the said outer extremities being turned downwardly to partially surround and form guards for the said front and back edges of the bottom member, said guide members 75 overlying a substantial part of the lower surface and approaching each other at their inner extremities, with a space between them.

5. In a wringer drain board, a bottom 80 member having two opposite edges turned up to form flanges, said flanges being notched at their upper edges for the reception of a wringer roll and guide members supported by said flanges on opposite sides 85 of the notches, said guide members covering a substantial part of the bottom member.

6. In a wringer drain board, a bottom member having two opposite edges turned up to form flanges, said flanges being 90 notched at their upper edges for the reception of a wringer roll, and guide members supported by said flanges on opposite sides 95 of the notches, and spaced from the bottom member to form wedge shaped pockets between the bottom member and the guide members and forming a covering for a substantial part of the bottom member.

7. In a wringer, a double drain board comprising upper surfaces and a lower surface, the upper surfaces diverging from the lower surface toward the middle thereof, said drain board having water delivery edges and drain openings adjacent said delivery edges.

8. In a wringer, a double drain board comprising upper surfaces and a lower surface, the former overlapping front and back edges of the latter and being spaced therefrom to form drain openings, the inner portions of the upper surfaces being spaced further from the lower surface than the outer portions thereof.

9. A wringer drain board comprising a lower water directing surface, adapted to occupy an inclined position on a wringer, an upper water directing surface spaced from the lower water directing surface, the water delivery edge of said upper surface being located beyond the water delivery edge of 115 said lower surface so that water traveling on the lower surface is released underneath said upper surface and within the marginal limits thereof.

In witness whereof, I hereunto subscribe 125 my name to this specification.

HAROLD W. EDEN.
